STRIKING DEVICE

Henry K. Ullman, Washington, D. C.

Application January 28, 1947, Serial No. 724,732

5 Claims. (Cl. 273—129)

1

This invention relates to amusement devices and more particularly to apparatus for striking a ball or movable playing piece in a novel and entertaining manner.

In toys, display devices and games it is common to provide a mechanically operated device for striking a ball or other playing piece. Some of these striking devices are intended for automatic operation when connected to a suitable power source and others are intended for manual operation. Both types may include certain adjustment features whereby the skill of the user is introduced into the operation thereof. Generally speaking, however, the prior art apparatus of this sort includes a striking element such as a bat, a club or a simulated limb which is either mechanically or manually moved into contact with either a movable or stationary ball or other playing piece. Most of these devices rely, for the introduction of player skill, upon a movement of the ball or other playing piece and do not afford opportunity for the exercise of player skill in conjunction with a stationary ball. For example, a common type of striking device is the pivoted bat which requires of the operator a sense of timing to swing it at the proper moment in order to engage a movable playing piece. Such a device, however, is clearly not susceptible of use with a stationary playing piece since the swinging action is so simple that the desired effect is quickly attained by all of the users of the device and its entertainment value is accordingly reduced.

It is an object of the present invention to provide a manually or mechanically operated striking device which may be used either with a moving or stationary ball or other playing piece and which introduces a lost motion between the driving element and the striking element in such a way that the exercise of considerable skill is required to produce a predetermined striking effect regardless of whether one strikes a moving or a stationary object.

It is contemplated in accordance with the present invention to produce a striking device which may be used in the playing of games, in displays and as a toy to project or displace a movable object such as a ball, and to provide for the variable application striking force to the ball and a variable ball trajectory whereby interesting and entertaining variation in the movement of the playing piece is afforded.

Other objects and advantages of the invention will be apparent upon consideration of the following detailed description of several embodi-

2

ments thereof in conjunction with the annexed drawings wherein:

Figure 1 is a top plan view of a game board illustrating a typical installation of the striking device of the present invention;

Figure 2 is a view partially in section and partially in side elevation taken along the line 2—2 of Figure 1;

Figure 3 is a view in section taken along the line 3—3 of Figure 1;

Figure 4 is a fragmentary view partially in section illustrating a modification of the invention;

Figure 5 is a perspective view illustrating in detail a portion of the modified apparatus of Figure 4; and

Figure 6 is a view similar to Figure 4 but illustrating still another modification of the invention.

20 Referring in greater detail to the drawings, and particularly to Figures 1—3 inclusive, an elongate, hollow box-like structure 10 is provided with a generally flat upper surface 11 which may simulate the surface of a playing field or 25 be otherwise decorated to meet the requirements of any particular installation. The long sides of the upper surface of the box-like structure 10 are provided with railings 12 projecting above the plane of the surface 11 and which act as 30 guides to restrain the undesired escape of a ball 13 from the playing surface. A similar rail or stop 14 is provided at one end of the playing surface. At the other end of the playing surface a striking device constructed in accordance with 35 the teachings of the present invention is provided. This striking device is comprised of a body portion 15, freely pivoted arm portions 16 and freely pivoted leg portions 17. A drive shaft or rod 18 passes through the body portion 15. 40 The shaft 18 may be in the form of a threaded bolt locked to the body portion against rotation relative thereto by a nut 19. A portion of the shaft 18 projects from the body portion 15 to the right of the nut 19, as shown in Figure 3, and this projecting portion is mounted for free rotation in a bearing 20 supported in a standard 45 21 which is suitably attached at its base to the playing surface 11. The end of the projecting portion of the shaft 18 which extends beyond the standard to the right thereof, as it is shown in Figure 3, is provided with a sheave 22 which is keyed thereto or otherwise affixed for rotation therewith. This sheave is connected by a belt 23, which may be a band of rubber or other 50 resilient material, to a sheave 24 mounted with-

in the box-like structure 10 on a bracket 25, a slot being cut in the surface 11 to permit passage therethrough of the band. The sheave 24 is keyed for rotation with a crank shaft 26 provided with a crank 27 which projects from one side of the box-like structure 10, see again Figure 3.

It is now apparent that rotation of the crank 27 will cause rotation of the sheave 24 which, through the belt 23, will drive the sheave 22 and the shaft 18 to cause rotation of the body portion 15 of the striking device about the axis of the pivot pin. This movement is not, however, directly imparted to the limbs 16 and 17 with the result that the limbs swing freely in response to gravity and centrifugal force about their respective axes at 28 and 29 which are parallel to the axis of the shaft 18. The arm simulating limbs 16 are limited in the magnitude of their angular movement about the axes at 28 by pins 30 and 31, while the leg simulating limbs are similarly limited by the pins 31 and 32. As can be seen in Figure 2, pin 31 acts as a stop pin for both the arm and leg simulating limbs on that side of the body portion. In view of the fact that the limb which is used for striking the ball 13 in the embodiment shown in the drawing is the left-hand leg simulating limb 17, as viewed in Figure 3, stop pins are not required for the respective right-hand limbs 16 and 17.

Adjacent and in front of the leg 17 which is located on the left side of the body portion, there is provided in the playing surface 11 a depression 33 of lesser width than the diameter of the ball 13 and of sufficient depth to act as a guide for the ball to retain the same in the plane of movement of the left-hand leg simulating limb 17 of the striking device. At the bottom of this depression there is provided a narrow elongate slot 34 the structure and function of which will be hereinafter more fully described. Ball guiding baffles 35 and 36 are provided on the surface of the playing surface 11 and ball receiving pockets or depressions 37 and 38 are provided at the end of the playing surface 11 remote from the striking device. Pins 39 are arranged to interfere with the progress of the ball between the depression 33 and the pockets 37 and 38 so as to render the striking of the ball to any of those pockets more difficult and interesting. A projection 40 directly in front of the pocket 38 performs a like function.

It can now be seen that if the ball is placed in the depression at 33 and the crank 27 is turned so as to rotate the body portion 15 in a clockwise direction, as viewed in Figure 2, the left-hand limb 17 will follow around behind the body portion and will fall to a position such as to strike the ball 13 and to cause it to be displaced toward the left-hand of the playing surface 11, as viewed in Figure 2. This movement is somewhat unpredictable and requires a high degree of skill for its satisfactory performance since the connection between the body portion 15 and the ring portion 17 is a free pivot and since the connection between the pulleys 24 and 22 is a resilient band. The ball will be engaged, however, and projected toward the left-hand of the playing field where it may become lodged in one of the receiving pockets 37 or 38, these pockets being assigned arbitrary scoring values corresponding to the difficulty encountered in causing the striking device to knock a ball into them.

Because of the elongate nature of the depression 33, the ball will not be displaced from guided position when the limb 17 touches it at the be-

ginning of its clockwise movement. At this time it will be moved slightly to the left of the Figure 2 position until the foot portion of the limb 17 clears it, and it will then fall back by gravity to a position lying in the path of the leg portion so that it can be kicked as the body portion 15 is rotated, the depth of the depression 33 increasing slightly in the direction of the right end of the surface 11 as viewed in Figure 2.

In Figures 4 and 5 there is shown a modification of the invention in which the ball is kicked upwardly to a marked extent. This arrangement may be made, for example, with simulated football goal posts or the like. The slot 34 in this case receives a guiding projection 41 on a wedge-shaped ball guide 42 which has a curved upper surface 43. The ball is placed in the curved surface 43 and is kicked in the manner shown in Figure 4. As the foot of the kicking limb is initially moved, the ball goes to the upper edge of the surface 43 and then falls back adjacent the lower edge as the body portion 15 is being rotated and at the moment of impact the ball is resting on the lower or left edge of the surface 43 so that when struck it is guided by that surface to assume a high trajectory.

A slightly modified form of the wedge of Figures 4 and 5 is shown in Figure 6. Here, however, the wedge which bears reference number 44 is associated with the depression 33 and assumes a forward position therein. The ball is kicked exactly as described in connection with Figures 1, 2 and 3 except that after being struck it engages the inclined surface of the wedge 44 and is given a high trajectory. Instead of using a wedge having a guiding projection as is indicated in Figures 4, 5 and 6, it is entirely feasible to use a flat bottom wedge which may be disposed in any position in front of the kicking limb of the device by merely resting it on the playing surface. This modification can be used with simulated goal posts and the goal posts and wedge both being subject to adjustment relative to the kicking device, afford a very large number of relative positions in which the ball may be kicked through the goal posts.

While this invention has been described with respect to its use in a game device, it is apparent that the kicker alone may be used as a toy or that several kickers might be associated together in a display device. It is also apparent that various modifications in the structure of the striking device, the selection of the limb used for striking and the operation of the device may be undertaken within the scope of the invention.

What is claimed is:

1. An amusement device comprising a support, an elongated body portion, means mounting said body portion for rotation about a horizontal axis above said support, a limb portion mounted on said body portion for free pivotal movement with respect thereto about a horizontal axis eccentric to said first-mentioned horizontal axis, said limb portion extending to a position adjacent said support when the point of its pivotal attachment to the body portion is nearest to said support and means for rotating said body portion so that an object resting on said support may be displaced by said limb portion.
2. An amusement device comprising a body portion, means mounting said body portion for rotation about a horizontal axis, a limb portion attached to said body portion for free pivotal movement with respect thereto about a horizontal axis eccentric to said first-mentioned horizontal

axis, said limb portion having a free end extending beyond the arc described by any part of the body portion in its rotation, a table to which said mounting means is attached and means supported by said table for rotating said body portion.

3. An amusement device as claimed in claim 2, further comprising driving means for rotating said body portion about the first-mentioned horizontal axis and resilient means connecting said driving means to said mounting means.

4. An amusement device as claimed in claim 2, further comprising stop means projecting from said body portion for limiting the magnitude of the pivotal movement of the limb portion relative to the body portion.

5. An amusement device comprising a body portion, means mounting said body portion for rotation about an axis, a limb portion attached to said body portion for free pivotal movement

with respect thereto about an axis parallel but eccentric to the first-mentioned axis, said limb portion having a free end extending beyond the arc described by any part of the body portion in its rotation and a table to which said mounting means is attached.
